PROP-WITHDRAWING APPARATUS FOR USE IN MINES

Filed Aug. 6, 1947

UNITED STATES PATENT OFFICE

2,597,807

PROP-WITHDRAWING APPARATUS FOR
USE IN MINESJohn Bridie Mavor, Glasgow, Scotland, assignor
to Mavor & Coulson, Limited, Glasgow, ScotlandApplication August 6, 1947, Serial No. 766,629
In Great Britain July 25, 1945

8 Claims. (Cl. 254—93)

1

It is the practice to support the roof of mine workings by means of props, usually made either of timber or steel. As the roof settles, the props become subject to heavy load. To withdraw loaded props, prop-withdrawing apparatus is used, this being apparatus by means of which a strong lateral pull can be applied to the foot or head of the prop, a high mechanical advantage being obtained from hand operation at a safe distance from the prop.

An object of this invention is to provide prop-withdrawing apparatus comprising a transportable body with a motor-driven pump for the supply of fluid under pressure, a fluid pressure cylinder-and-ram unit operated by fluid from the pump, and an attachment device for connecting said unit to either the foot or the head of the prop to be withdrawn so as to exert the required pull on the prop.

Another object of this invention is to provide a vehicle with a fluid supply, a motor-driven pump drawing from said supply, a cylinder-and-ram unit, a valve for controlling the operation of said unit, and an attachment device on said unit by virtue of which the unit can be connected to either the foot or the head of a prop in order to exercise thereon a pull sufficient for withdrawal thereof.

The apparatus may be anchored to an appropriately set roof-supporting prop as is customary with hand-operated apparatus, or the apparatus may have provision of its own for anchorage.

The invention will now be described by way of example with reference to the accompanying drawing, in which—

Fig. 1 is a side elevation of one construction of the apparatus including a wheeled vehicle, this view showing the apparatus positioned for use. Fig. 2 is an end elevation of the vehicle. Fig. 3 is a side elevation of the vehicle showing it at rest in an out-of-use position.

Fig. 4 is a view corresponding to Fig. 2, but showing a construction in which the vehicle is adapted to slide on a mine floor.

Referring to Fig. 1, the apparatus shown therein is positioned for use upon the floor A of the mine. The roof B of the mine is shown supported by a prop C about to be withdrawn by the apparatus.

In the construction of the apparatus according to Figs. 1 to 3, the body of the wheeled vehicle includes an under-carriage 6 provided at opposite sides with wheels 7 having an axle 8. The body also includes a horizontal hydraulic cylinder 9 which is arranged centrally at a low level, being

2

at the level of the axle 8. The body also includes at a level above the hydraulic cylinder an oil tank 10, a motor 11 (which may be either an electric motor or a compressed air motor), a pump 12 driven by the motor, and a control valve 13 having a hand-lever 14 for setting the valve in any of various available positions. The pump 12 is conventionally shown in Fig. 1, being of a type which is coupled directly to the motor 11 without speed-reducing gearing. The pump is arranged in the oil tank 10, the suction side of the pump drawing oil directly from the tank. The discharge side of the pump is connected by a pipe 15 to the valve 13. Pipes 16 and 17 connect the valve 15 to opposite ends of the hydraulic cylinder 9. A return pipe 18 leads from the valve back to the oil tank. The cylinder 9 is a component of a hydraulic unit including also a ram 19 which protrudes from one end of the cylinder (the left-hand end in Fig. 1). The outer end of the ram is provided with a pivotal device 20 for attaching the ram to a cable 21, one end 22 of which is connected to a clamp 23 secured to the foot of the prop C. The attachment device 20 may be of any appropriate construction, the example shown comprising two jaws 24 and 25 under the control of a manually turnable eccentric 26, the function of which is to force the upper jaw 24 to grip the cable 21 hard against the lower jaw 25. The attachment device is in the nature of a one-way clutch, the arrangement being such that the stronger the pull on the cable, the stronger the grip exercised by the jaws. At that end of the vehicle which is opposite to the ram (the right-hand end, Fig. 1), a prop socket 27 is attached by a pair of side links 28 to the axle 8, this socket being adapted to receive the foot of an anchorage prop 29 which in the construction shown is telescopic, being made of steel and having pointed end fixtures 30 adapted to bite into the floor A and the roof B. The lower part of the vehicle is provided with a skid 31 upon which the vehicle rests when out of use (Fig. 3).

In order to use the apparatus, it is moved along the floor A of the mine into an appropriate position in relation to the prop C, which is usually set as shown at an inclination to the vertical. The anchorage prop 29 is fitted through the socket and is extended so that it is jammed between the floor and roof at an appropriate inclination. In this way the apparatus is accurately anchored in its chosen location.

The motor 11 is started and drives the pump 12. The hand-lever 14 of the control valve is turned so that oil under pressure is admitted by

way of the pipe 16 to the right hand end of the hydraulic cylinder 9, the left hand end thereof being connected through the pipe 17, valve 13 and pipe 18 to the oil tank 10. Accordingly, the ram 19 is projected from the hydraulic cylinder. When the ram is sufficiently projected, the hand-lever is turned to its neutral position (in which the oil circulates idly through the pump, valve and tank). The cable is attached to the prop C to be withdrawn and is pulled towards the right through the attachment device 20 until it is taut. The eccentric 26 is manipulated so that the jaws 24, 25 securely grip the cable. Then the hand-lever 14 is positioned so that oil under pressure is delivered from the pump by way of the pipe 17 to the left-hand end of the cylinder, oil from the other end thereof being returned to the oil tank by way of the pipes 16 and 18. Accordingly the ram is forcibly withdrawn into the cylinder and exerts on the prop C a pull which is strong enough to withdraw the prop.

In the drawing (Fig. 1), the clamp 23 is shown secured to the foot of the prop C. It often happens however that the securing must be done at the head. By virtue of the pivotal relationship, through the axle 8, between the hydraulic unit 9, 19 and the links 28, the hydraulic unit can be upturned into a position (namely, the rest position according to Fig. 3) in which said unit is aligned with a pull directed to the head of the prop, there being a sufficient length of cable 21 for the purpose. Thus it will be manifest that the pull to the head of the prop can be exerted without any tendency whatsoever to lift the vehicle from the floor (a tendency which would be of the greatest danger in a coal-mine). Moreover, it will be manifest that the pull (whether to the foot or head of the prop) is taken through the pivotally interconnected hydraulic unit 9, 19 and links 28, the vehicle itself being relieved from stresses due to the pull except as regards the desirable downward pressure holding the vehicle to the floor.

In the construction according to Fig. 4, the vehicle is the same as described with reference to Figs. 1 to 3 with the exception that the vehicle is not wheeled but has a base in the form of a skid 32 which can slide upon the mine floor A. The skid 32 is supported by side struts 33 which hang from the axle 8 of the undercarriage 6. It will be manifest that, in this construction, the hydraulic cylinder 9 (with the remainder of the body of the vehicle) is pivotal in relation to the floor-engaging supporting means 32, 33, just as in the construction according to Figs. 1 to 3 the cylinder is pivotal in relation to the floor-engaging wheels 7. Thus, the unit 9, 19 can be directed towards either the foot or head of the prop to be withdrawn.

The constructions described are examples, and any of various modifications may be made. For instance, Fig. 1 shows the cable 21 as a rope; instead, it may be a chain, and the attachment device may be such that the cable is positively locked to the ram end.

I claim:

1. Mine prop-withdrawing apparatus comprising a transportable body with supporting means to engage the floor and a motor-driven pump for the supply of fluid under pressure, a fluid-pressure cylinder-and-ram unit operated by fluid from the pump, a pivotal connection between said unit and said supporting means by virtue of which the unit can be directed towards either the foot or head of a prop to be withdrawn, and

5 an attachment device for connecting said unit to either the foot or the head of the prop to be withdrawn so as to exert the required pull on the prop.

2. Mine prop-withdrawing apparatus comprising a vehicle with supporting means to engage the floor and a fluid supply, a motor-driven pump drawing from said supply, a cylinder-and-ram unit operable by the fluid from the pump, a valve for controlling the operation of said unit, a pivotal connection between said unit and said supporting means by virtue of which the unit can be directed towards either the foot or head of a prop to be withdrawn, and an attachment device on said unit by virtue of which the unit can be connected to either the foot or the head of the prop in order to exercise thereon a pull sufficient for withdrawal thereof.

20 3. Mine prop-withdrawing apparatus comprising a transportable body with supporting means to engage the floor and a motor-driven pump for the supply of fluid under pressure, a fluid-pressure cylinder-and-ram unit operated by fluid from the pump, a pivotal connection between said unit and said supporting means by virtue of which the unit can be directed towards either the foot or head of a prop to be withdrawn, an attachment device for connecting said unit to either the foot or the head of the prop to be withdrawn so as to exert the required pull on the prop, and means connected to said unit for anchoring the transportable body to a mine floor so that the pull is exerted through said unit and said anchoring means.

35 4. Mine prop-withdrawing apparatus as claimed by claim 3 in which the anchoring means consist of a linkage pivotally connected to and extending from said body and a socket on said linkage to receive an anchorage prop.

40 5. Mine prop-withdrawing apparatus comprising a vehicle with supporting means to engage the floor and a fluid supply, a motor-driven pump drawing from said supply, a cylinder-and-ram unit operable by the fluid from the pump, a valve for controlling the operation of said unit, a pivotal connection between said unit and said supporting means by virtue of which the unit can be directed towards either the foot or head of a prop to be withdrawn; an attachment device on said unit by virtue of which the unit can be connected to either the foot or the head of the prop in order to exercise thereon a pull sufficient for withdrawal thereof, a linkage pivotally connected to and extending from said vehicle, and means on said linkage for attachment thereof to an anchorage prop.

45 6. Mine prop-withdrawing apparatus comprising a transportable body with supporting means to engage the floor and a motor-driven pump for the supply of fluid under pressure, a fluid-pressure cylinder-and-ram unit operated by fluid from the pump, said unit comprising a movable component and a stationary component which is pivotally mounted in relation to said supporting means so that said unit can be directed towards either the foot or head of a prop to be withdrawn, and an attachment device provided on said movable component for connecting it to a cable attachable to either the foot or the head of the prop to be withdrawn so as to exert thereon a pull sufficient for withdrawal thereof.

50 7. Mine prop-withdrawing apparatus comprising a vehicle with supporting means to engage the floor and a fluid supply, a motor-driven pump drawing from said supply, a cylinder-and-ram

unit operable by the fluid from the pump, said unit comprising a movable component and a stationary component which is pivotally mounted in relation to supporting means so that said unit can be directed towards either the foot or head of a prop to be withdrawn, a valve for controlling the operation of said movable component, and an attachment device provided on said movable component for connecting it to a cable attachable to either the foot or the head of the prop in order to exercise thereon a pull sufficient for withdrawal thereof.

8. Mine prop-withdrawing apparatus comprising a vehicle with supporting means to engage the floor and a fluid supply, a motor-driven pump drawing from said supply, a cylinder-and-ram unit operable by the fluid from the pump and consisting of a cylinder, which is a fixture on the vehicle but is pivotal in relation to said support-

ing means, and a ram which is movable in and extends from said cylinder, a valve for controlling the operation of said ram, and an attachment device on said ram by virtue of which the ram can be connected to either the foot or the head of a prop in order to exercise thereon a pull sufficient for withdrawal thereof.
